[57] CLAIM

The ornamental design for a skill and chance game board, as shown and described.

DESCRIPTION

FIG. 1 is a top plan view of a skill and chance game board showing my new design, this figure of the drawing being lined to show contrasting colors;

FIG. 2 is a side elevational view thereof, each of the three remaining sides being a mirror image of that shown in FIG. 2;

FIG. 3 is a full sectional view taken along the line 3—3 of FIG. 1;

FIG. 4 is a partial sectional view taken along the line 4—4 of FIG. 1; and

FIG. 5 is a bottom plan view thereof.

FIG. 1

FIG. 2

FIG. 3

FIG. 4**FIG. 5**
